FIG. 1 is a top plan view of a clog showing my new design;

FIG. 2 is a side elevational view thereof showing the employment of a low heel;

FIG. 3 is a rear elevational view; and

FIG. 4 is a side perspective view thereof.

FIG. 5 is a top plan view of a second embodiment of the clog shown in FIG. 1;

FIG. 6 is a side elevational view of the second embodiment of FIG. 5 showing the employment of a high heel;

FIG. 7 is a rear elevational view; and

FIG. 8 is a side perspective view thereof.

This application is a continuation of my copending applications Serial Nos. D-75,238 and D-75,239 both filed on June 5, 1963, and now abandoned.

I claim:

The ornamental design for a clog or similar article, substantially as shown and described.
